CLAIM

We claim the ornamental design for a clamp sensor, as shown and described.

DESCRIPTION

FIG. 1 is a front elevational view of a clamp sensor, showing our new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a perspective view thereof, showing the clamp part closed; and,

FIG. 8 is a perspective view thereof, showing the clamp part open.

1 Claim, 8 Drawing Sheets
